Des. 209,220
Patented Nov. 14, 1967

209,220

CRAWLER-TYPE TOY VEHICLE

John W. Ryan, Bel Air, and Gerald W. Schmidt, Tarzana, Calif., assignors to Mattel, Inc., a corporation of California

Filed Dec. 21, 1966, Ser. No. 5,133

Term of patent 14 years

(Cl. D34—15)

FIG. 1

FIG. 2

FIGURE 1 is a perspective view of a crawler-type toy vehicle showing our new design;

FIGURE 2 is a front end elevational view thereof;

FIGURE 3 is a side elevational view of the opposite side of FIG. 1; and

FIGURE 4 is a bottom plan view of the design.

We claim:

The ornamental design for a crawler-type toy vehicle, as shown.
